Wm. Bagger.

Inventor

James W^m. Green

UNITED STATES PATENT OFFICE.

JAMES WM. GREEN, OF ALBINA, OREGON.

SAW-FILING MACHINE.

SPECIFICATION forming part of Letters Patent No. 415,106, dated November 12, 1889.

Application filed July 22, 1889. Serial No. 318,297. (No model.)

To all whom it may concern:

Be it known that I, JAMES W. GREEN, a citizen of the United States, residing at Albina, in the county of Multnomah and State of Oregon, have invented a new and useful Saw-File, of which the following is a specification.

This invention relates to an improved device for filing saws; and it consists of a cylindrical file having one or more spiral threads adapted to engage and operate upon the teeth of a saw, which, while acted upon by the file, is automatically moved forward, thus causing the teeth to be sharpened more evenly and accurately and much more rapidly than can be done by means of a file of the ordinary description.

The invention consists, mainly, in the improved construction of the said file and incidentally in the frame for holding and operating the same, as will be hereinafter described, and pointed out in the claim.

In the drawings, Figure 1 is a side view of a saw-file embodying my improvements. Fig. 2 is an end view of the same. Fig. 3 is a top view showing the same arranged in a frame having mechanism whereby it may be operated. Fig. 4 is a side view of the device shown in Fig. 3, and Fig. 5 is a top view showing a saw in position for being filed.

The same parts in the several figures are indicated by like numerals of reference.

In the drawings, 1 designates the cylindrical body of my improved file, which is provided with one or more spiral threads or flanges 2, which in section are shaped to fit the teeth of the saw for which the file is specially adapted, and which are toothed or serrated in the manner in which saw-files are usually constructed.

With regard to the detailed construction of the file I would here have it understood that I do not limit myself either with respect to the number of spiral flanges or to the particular shape of said flanges, inasmuch as these features will necessarily have to be varied, according to the kind and character of saw for which the file is adapted. Thus for fine cross-cut-saws one kind of spiral flanges would be required, while for rip-saws flanges of entirely different construction would be preferable. Neither do I deem it necessary to explain in detail the construction of said flanges,

inasmuch as this will be readily understood by any one skilled in the art to which the invention appertains. Again, the flanges in some files will be in the form of right-hand spirals, while in others the spirals will be left hand. Thus for the purpose of filing a cross-cut-saw two files—one right and one left handed—would be employed to properly file the alternate teeth of such saw.

One form of an operating-frame which may be conveniently used in connection with my invention has been shown in the drawings hereto annexed. Said frame consists of a bed-plate 3, having bearings for a short shaft 4, upon the front end of which is mounted a pinion or bevel-gear 5. A bracket 6, attached to and extending laterally from the bed-plate, is provided with bearings for an operating-shaft 7, having at its rear end a crank 8 and at its front end a pinion 9, meshing with the bevel-gear 5. The rear end of the shaft 4 has a polygonal stud 10, adapted to engage the correspondingly-shaped socket 11 in the front end of the cylindrical body 1 of the file. The rear end of said body is provided with a recess 12, adapted to be engaged by a pintle 13 at the front end of a shaft 14, mounted to slide longitudinally in a box or bearing 15 upon the bed-plate 3. A set-screw 16 in said box serves to retain the shaft 14 in any position to which it may be adjusted.

It will be seen that the described construction of the frame enables the file to be placed in position for operation in a moment's time, and that by operating the crank 8 a rotary motion will be imparted to the said file. The shaft 7 may be driven by hand by means of the crank 8, or it may be geared in any suitable manner to any convenient source at all. The bed-plate 3 is provided on its upper side with shoulders 17, against which the saw may be rested while it is being operated upon by the file.

The operation of the invention will be readily understood from the foregoing description, taken in connection with the drawings hereto annexed. The saw which is to be operated upon is placed with its teeth at one end in engagement with the file, which latter is then revolved in the manner described. The saw will thus be caused to travel along the file, whereby the teeth are sharpened evenly and

accurately. The operation may be repeated as often as may be deemed necessary.

The construction of my improved saw-filing device is exceedingly simple, and it is capable 5 of being operated by an unskilled person with satisfactory results.

Having thus described my invention, what I claim, and desire to secure by Letters Patent, is—

- 10 As an improvement in saw-filing devices, the combination, with a frame comprising a bed-plate having shoulders or guides, a shaft mounted permanently in bearings upon said bed-plate and having a pinion at one end, a longitudinally-movable shaft mounted in a bearing in said bed-plate in a line with the 15 axis of the permanent shaft, a laterally-ex-

tending bracket, and a counter-shaft journaled in said bracket, and having a crank at its outer end and a pinion at its inner end 20 meshing with the pinion upon the permanent shaft, of a screw-shaped or cylindrical spirally-threaded file mounted detachably between the permanent and the adjustable shafts, substantially as and for the purpose 25 set forth.

In testimony that I claim the foregoing as my own I have hereto affixed my signature in presence of two witnesses.

JAMES WM. GREEN.
